(57) **CLAIM**

The ornamental design for a floor dimmer switch, as shown and described.

DESCRIPTION

FIG. 1 is a top / side perspective view of a floor dimmer switch;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines in the drawings illustrate features of a floor dimmer switch that form no part of the claimed design.
